United States Patent Office

Des. 183,553

Patented Sept. 23, 1958

183,553

SYRINGE HOLDER

Anthony J. Bayuk, Youngstown, Ohio

Application April 22, 1957, Serial No. 45,810

Term of patent 14 years

(Cl. D83—1)

Figure 1 is a perspective view showing the front and left side of a syringe holder embodying my new design; and Figure 2 is a perspective view of the rear and right side thereof.

I claim:

The ornamental design for a syringe holder, as shown.
